UNITED STATES PATENT OFFICE.

JOHN TAMBERLIN, OF PHILADELPHIA, PENNSYLVANIA, ASSIGNOR TO THE GEORGE W. BLABON COMPANY, OF PHILADELPHIA, PENNSYLVANIA, A CORPORATION OF PENNSYLVANIA.

MEANS FOR LUBRICATING LINOLEUM-DIE MECHANISMS.

Application filed November 2, 1920. Serial No. 421,279.

To all whom it may concern:

Be it known that I, JOHN TAMBERLIN, a citizen of the United States, residing in the city of Philadelphia, county of Philadelphia, and State of Pennsylvania, have invented certain Improvements in Means for Lubricating Linoleum-Die Mechanisms, of which the following is a specification.

My invention is designed to provide means for automatically lubricating surfaces of an inlaid linoleum machine with which sheeted linoleum composition contacts in the operations of translating and punching it, for the purpose of preventing the linoleum composition from sticking to said surfaces.

The improvements are particularly adapted for application to inlaid linoleum machines having pattern plates in which tesseræ are deposited by reciprocating cutting dies and stripper plates for disengaging the punched sheets from the dies, the tesseræ being carried by such pattern plates into position to be deposited on the backing material.

In its preferred form, my improvements comprise a lubricant distributor fed from a fount which is movable vertically with dies and stripper plate to supply the lubricant, the distributor being movable with the pattern plate carriage over the dies and stripper plate, and a second lubricant distributor and fount for feeding the same, which are carried by the machine frame and over which the pattern plate is movable.

The drawing is a broken sectional view showing part of a linoleum machine having my improvements applied thereto.

The mechanism illustrated comprises the frame members 1 to which the head 2 is fixed by the tie rods 3. A reciprocable block 4, having thereon the dies 5 and stripper plate 6 supported by the springs 7, is carried through the bearings 8 by the revoluble cams 9 fixed on the journalled shafts 10, the latter being driven and revolved in unison by the meshing spur wheels 11 fixed thereon.

A die plate 12 is carried by a carriage 13 comprising the rack bars 14 movable on the ways 15, the plate being suspended from the frame by the hangers 16 having a limited movement therein.

It will be understood that, when a sheet

is placed between the plates 6 and 12 in the lowered position of the dies 5, upon the elevation of the block 4, the sheet will be punched and the punched shapes will be set in the die plate as its upward movement is stopped by its engagement with the carriage 13, this plate with the shapes therein falling a limited distance as the block recedes and the stripper plate rises relatively to the dies to clear them of the punched sheet.

A lever 17, fulcrumed in a hanging bearing 18, is provided at one end with a weight 19 and at the other with a roller 20 which is held by the weight in engagement with the cam 21 fixed to and revolved by one of the shafts 10. The lever 17 has a link 22 pivotally connected thereto, at one end thereof, concentrically with the roller 20, the other end of the link being pivotally connected to a lever 23 having the fulcrum 24 on the frame.

The free end of the lever 23 is pivotally connected to one end of a link 24' which has its opposite end pivotally connected to a gear quadrant 25, the quadrant having the counterweight 26 and being fulcrumed on the bearing 27.

The quadrant 25, oscillated by the revolving cam 21 through the intermediate links and levers described, engages and rocks a spur wheel 28 journalled by means of a shaft 29 and having spur wheels 30 fixed thereto. A wheel 30 drives a gear wheel 31 journalled by means of a shaft 32 and the wheels 30 reciprocate the rack bars 14 on the ways 15.

The shaft 32 carries a sprocket wheel 33 which is revolved by the wheel 31 to which it is fixed, the sprocket wheel driving a chain 35 which passes over and drives a sprocket wheel 36 fixed on a journalled shaft 37. This shaft is provided with the sprocket wheels 38 and the friction drum 39, the former driving the chains 40 and the latter carrying the punched sheet.

The chains 40 pass under the idler sprocket wheels 41 and over the sprocket wheels 42 which are fixed to and revolve the friction drum 43 carried by the shaft 44 and carrying the sheet 45 to be punched.

The nipper bars 46 and 47, movable with the chains 40, engage the sheet 45 and carry it through the mechanism above the dies 5

and stripper plate 6 and beneath the die plate 12.

The lower nipper 47 has a strip 48, such as felt, fixed to and depending therefrom so that it will sweep over the dies 5 and the plate 6 in the lowered position thereof, as the wheels 30 advance the racks 14 and the nipper bars 46 and 47 draw the sheet 45 over these parts 5 and 6 and under the die plate 12, the felt having been saturated with a lubricant in the fount 44 carried by the block 4 as the latter rises and applying the same to the top surfaces of the parts 5 and 6 in the rearward as well as the forward 15 movement of the carriage 13.

A fount 49 supported by a bearing 50 on the frame 1 is provided with a wiper 51, suitably of felt, which is carried by a rod 52 so that its lower part dips into a lubricant in the fount and its upper part will contact with the bottom of the die plate 12 as it reciprocates thereover, the wiper being adapted by the rod to be rocked a limited distance by the contact of the plate therewith. Consequently, the bottom of the die plate is kept lubricated by the wiping action of the lubricating device 51 through which the lubricant is carried by capillary action.

Having described my invention, I claim:

30 1. In a machine of the character described, the combination with linoleum cutting mechanism and linoleum translating mechanism, of means comprising a lubricant font movable by one of said mechanisms and a wiper movable by the other of said mechanisms independently of said font for lubricating parts of said machine contacting with material cut thereby.

35 2. In a machine of the character de-

scribed, the combination with tesserae cutting and translating mechanisms comprising vertically reciprocating dies provided with a stripper plate and a transversely movable die plate, of lubricating means comprising a wiper movable with said die plate over said dies and stripper plate.

3. In a machine of the character described, the combination with tesserae cutting and translating mechanisms comprising dies and a movable die plate, of a lubricant distributor carried by the translating mechanism over said dies, and a second lubricant distributor over which said die plate is movable.

4. In a machine of the character described, the combination with a reciprocating carriage and a die plate carried thereby, of a lubricant distributor connected with said carriage, reciprocating punching mechanism in contact with which said distributor is movable by said carriage, and a fount connected with and reciprocated by said punching mechanism for supplying a lubricant to said distributor.

5. In a machine of the character described, the combination with vertically reciprocating dies and a stripper plate therefor, of a reciprocating carriage and a die plate carried thereby, a lubricant distributor movable with said carriage over said dies and stripper plate, a lubricant distributor in the path of and adapted to apply a lubricant to said die plate, and reservoirs for feeding lubricant to said distributors.

Signed at Philadelphia, in the county of Philadelphia and State of Pennsylvania, this 22nd day of October, 1920.

JOHN TAMBERLIN.
